UNITED STATES PATENT OFFICE.

ALMA E. GRADY, OF GARDENA, CALIFORNIA.

CURTAIN-ROD HOOD.

1,382,973.

Specification of Letters Patent. Patented June 28, 1921.

Application filed September 15, 1920. Serial No. 410,396.

To all whom it may concern:

Be it known that I, (Mrs.) ALMA E. GRADY, a citizen of the United States, residing at Gardena, in the county of Los Angeles and State of California, have invented certain new and useful Improvements in Curtain-Rod Hoods, of which the following is a specification, reference being had to the accompanying drawings.

10 In hanging lace curtains considerable difficulty has been experienced in passing the small brass rods through the fold of the curtain, owing to the sharp edges of the sheet metal at the open ends of the rods being unprotected. This difficulty has been more or less experienced when using the curtain rods consisting of two telescopic sections, as only one section is passed through the fold of the curtain, after which it is 20 united to the other section.

The purpose of this invention is to provide a cap which may be permanently carried by the ends of the rod, or may be used as a tool or a protector or shield for one end 25 of one of the sections of a sectional curtain rod, to facilitate the passage of the rod or section through the fold of the curtain, without the sharp edge of the sheet metal of the rod catching in the lace of the curtain, which 30 not only hinders the passage of the rod or section, but very often damages the curtain.

Hence, it is a further purpose of the invention to provide a hood or thimble of cylindrical contour, to telescope the end of 35 the rod or the end of the section, and provide it with a rounded end, so as to permit of the passage of the curtain rod section through the fold, without tearing the curtain or hindering the passage of the rod.

40 It has been found that by providing the hood (which may be any suitable length preferably an inch or more) with corrugations, the hood may be expanded, thereby facilitating the attachment of the hood to 45 the rod or to the section. For instance, should the hood be made without the corrugations, and just large enough to frictionally engage the end of the rod or section, it would be more or less difficult to register the hood 50 with the end of the rod or section, so as to cause the insertion of the rod into the hood, hence the provision of the corrugations. Also by providing the corrugations, the hood can be made so as to require an expansion 55 of the hood, or a contraction of the end of the rod to cause the two to engage each other,

and in this way the surfaces of the corrugations extending inwardly of the hood, will frictionally bite on the rod and hold the hood in place.

60 While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the 65 scope of what is claimed.

The invention comprises further features, 70 and combination of parts, as will be herein-after set forth, shown in the drawings and claimed:—

In the drawings:—

Figure 1 is a view in perspective of a portion of a curtain showing a curtain rod being passed through the fold thereof, and showing the end of the rod as provided with a hood, to insure the passage of the rod through the fold without injury to the curtain, and without retarding the passage of the rod.

Fig. 2 is a sectional view through the curtain rod showing the hood applied,

Fig. 3 is a cross sectional view, and

Fig. 4 is an enlarged detail view of the hood.

Referring especially to the drawings, 1 designates a conventional form of tubular sheet metal curtain rod, and 2 denotes the 90 unprotected end, and 3 the hood. This hood may be any suitable length, preferably an inch or more and also cylindrical. The hood at its closed end is rounded, so as to facilitate the easy passage of the rod through the 95 fold of the curtain without injury to the curtain. The cylindrical wall of the hood is provided with corrugations 4, which merge into the rounded end 5 of the hood. It will be noted that these corrugations will permit 100 of a slight expansion of the hood, in order to increase its size, and cause the easy fitting of the hood on to the end of a rod, and owing to there being a certain amount of resiliency, or a tendency to contract after the 105 expansion of the hood, the hood will be held frictionally on the rod.

The invention having been set forth, what is claimed as new and useful is:—

1. A protecting hood for curtain rods, 110 comprising a cylindrical hollow body having an open end and a closed end, and

- adapted to telescope a curtain rod to shield the sharp edges of the open end of the curtain rod as it passes through the fold of the curtain, the closed end being rounded to 5 facilitate an easy passage of the hood through the fold of the curtain and to prevent catching in the fabric of the curtain, the wall of the cylindrical body having a plurality of longitudinally extending corrugations, permitting of an expansion of the 10 cylindrical wall, when applying the hood to end of the rod, said longitudinal corrugations merging into the rounded closed end of the hood.
2. As an article of manufacture, a curtain rod cap, comprising a cylindrical body having a contiguous sheet metal wall, said cap having one end closed and its other end open, said contiguous wall having expandible corrugations extending from the open end and terminating closely adjacent the closed end, permitting the cap to expand for facilitating the insertion of the rod into the open end of the cap.
- In testimony whereof I hereunto affix my 25 signature.

ALMA E. GRADY.
